ELECTRIC CIRCUIT BREAKER

Josef Biermanns, Berlin-Johannisthal, Germany,
assignor to General Electric Company, a corporation of New York

Application November 11, 1936, Serial No. 110,398
In Germany September 20, 1935

11 Claims. (Cl. 200—148)

This invention relates to electric circuit breakers of the fluid-blast type wherein an arc-extinguishing fluid such as, for example, air or carbon dioxide under pressure, is directed into the arc path for interrupting the circuit.

In the types of fluid or gas blast circuit breakers heretofore proposed the arc-extinguishing agent is generally directed as a single jet transversely of the arc thereby tending to elongate the arc and increase the arc pressure. Multiple jets, acting transversely of the arc and independently of each other, have also been proposed and tend to produce generally the same result.

An essential factor in arc interruption is the primary cooling of the arc and subsequent penetration thereof by the comparatively cold extinguishing agent to form a layer between the circuit breaker electrodes that is puncture-proof with respect to the circuit recovery voltage. The surface cooling enables the extinguishing agent to enter laterally into the arc and shift one of its base points or roots. This is effected in an improved manner in accordance with the present invention by spatial penetration of the arc body by means of two jets of arc-extinguishing fluid which are directed against each other so as to agitate and produce transverse as well as longitudinal fluid currents in the arc stream. These transverse currents formed at the point where the fluid jets impinge on one another, tend to establish a dielectric layer for preventing re-ignition of the arc after interruption at a current zero.

In carrying out the invention a circuit breaker electrode or contact structure, and preferably also the counter-electrode, are subjected to two jets of the arc-extinguishing agent, the two jets being directed towards one another in such a manner that they envelop the arc in hose-like fashion and produce transverse currents in and agitation of the arc at the point of opposition. In practice, this can be accomplished by directing the jets of the extinguishing agent towards one another from annular jet guide members having a common axis and arranged in opposition to each other. The jet guide members at the exhaust portions thereof are preferably each provided with an annular member flared outwardly from the contact point so as to assume the shape of a hood. These hoods can function as screens or shields for preventing re-ignition of arcing by the heated arc gases.

My invention will be more fully set forth in the following description referring to the accompanying drawing, and the features of novelty

which characterize my invention will be pointed out with particularity in the claims annexed to and forming a part of this specification.

The invention is illustrated diagrammatically and by way of example on the accompanying drawing on which Figure 1 is partly a side-view of, and partly an axial section through, one of the contacts and associated structure. Figure 2 is a plan view and shows the invention combined with a power separation switch, the portion at the left-hand end being shown in section. Figure 3 is a view in which two devices of the kind shown in Fig. 1 are arranged oppositely to one another.

Referring to Fig. 1, there is provided relatively 15 movable contact structure including a pin-shaped electrode or contact 2 in an envelope 1 designed as a hollow ball-calotte, or hood respectively, which also serves for the homogenization of the electric field and as radiation protection. 20 Between said electrode 2 and the inner wall of a coaxial tube 3 connected with the envelope 1 is formed a tubular space 4 serving for the passage of the arc-extinguishing fluid or gas under pressure. The gas flows over the electrodes so that 25 the gas issuing forth from said space 4 envelops the arc, in the proximity of its root or base, like a hose, whereby the arc root is fixed at the desired place and cooled intensely. The electrode shown in Fig. 1 with its envelope 1 that constitutes an 30 electrostatic screen, as well as the counter-electrode (not shown in Fig. 1), which may be of the same design as the electrode shown or may have any other suitable shape, and be likewise, arranged in an envelope of appropriate design, are 35 in the open air.

The hood-like envelope 1 (Fig. 1) is flared away from the exhaust opening of the annular passage 4 and is flattened on that side which is located opposite the counter-electrode (not shown, as 40 already stated) whereby a supporting or contacting surface for the counter electrode arranged substantially convex with respect thereto (when the device has been switched-on) is formed. The envelope 1 consists of metal and is preferably 45 provided with a layer of some suitable insulating substance or composition, especially at the places located opposite the pin-shaped electrode 2. There is by this means prevented in a reliable manner flash-over of a high voltage arc 50 between the electrode and envelope.

Another contrivance to prevent the arc from jumping over to the envelope consists in letting the head 5 of the electrode 2 which may consist of an arc resistant metal, for instance tung-

sten, project a little beyond the top face of the envelope 1 when the device is in switched-off state.

If two co-acting electrodes are used a particular effect will be attained whereby the jets of the gas under pressure which are directed towards one another and envelop the arc cylindrically bring about a strong whirling-through agitation of the arc with fresh air when they 10 impinge upon one another.

The arrangement may be so designed that when the device is being switched-on the envelope and the electrode change their position relatively to one another, for which purpose 15 either the envelope or the electrode is movable. Such an arrangement is shown, described and claimed in my co-pending application, Serial No. 109,561, filed November 6, 1936, for Electric circuit breaker.

20 In a practical constructional form of the invention as applied to a rotary separating or disconnecting switch the switching or arc chamber is formed by a pair of nozzle-like electrode structures associated with electrostatic screens 25 serving as protective envelopes. As in the previous instance, an annular gap between the electrode and the envelope is formed through which a jet of gas under pressure is directed so as to envelop the arc in hose-like fashion. The arc is cooled by the jet or jets when deflected in the manner above described. Flash-over of the arc to the protecting envelopes is effectively prevented by the guiding effect of the gas cylinder that envelops the arc.

30 In the arrangement shown in Fig. 2 only one of the electrodes (2) is designed as a pin, whereas the counter-electrode 6 is of the segmental type and, if desired, may be extended in length so as to resemble a nozzle. With this arrangement the envelope 1 is shiftable upon the pin-shaped electrode 2, for which purpose the envelope is connected with a sleeve 7 subjected to the action of a helical compression spring 8. The sleeve 7 is guided in a tubular guide member 9 attached to a supporting insulator 10 which also is used for the supply of the gas under pressure. The electrode 2 may be stationary, as shown in Fig. 2, or may likewise be shiftable. The annular passage 4 (Fig. 1) through which 40 the gas under pressure is supplied is located in Fig. 2 between the electrode 2 and the sleeve 7. The counter electrode is enclosed in a sleeve 11 affixed to a double-arm 13 turnable on a pivot 12. The other arm of 13 is equipped with 45 precisely such a set of members as are on the left-hand side.

50 When the switch is switched-on, the envelope 11 which is likewise flat at its free top-face contacts with the correspondingly shaped free top face of the envelope 1 (position of the parts shown in Fig. 2). When the envelope 11 is further moved, in the same direction, the envelope 1 will give way, counter to the pressure of the spring 8, and the electrode 2 will enter into the 55 suitably shaped counter-electrode 6. The spring 8 is now able to cause the automatic separation of the electrodes when the switch is to be switched-off.

60 The switch arrangement described can be designed and used also for multiple interruption.

In the further constructional form shown in Fig. 3 the electrode 31 is again shaped as a pin and housed in a tubular guide member 32 in such a manner that a tubular space 33 is 65 formed through which the extinguishing agent

is supplied. The member 32 may also in this case be combined with a tubular hood 34 which, especially if the electrodes are, or the arc respectively is, subjected to the blast or blasts of said agent in the open air, may consist of metal 5 and may have an insulating covering for the prevention of flash-over of the arc and for homogenizing the electric field between the electrode and the counter-electrode 31' (right-hand half of Fig. 3). The electrode 31, or the hood 10 34 respectively, may be either stationary or movable in order to facilitate the closing and the separation of the contacts when switching takes place. The jet of the extinguishing agent passes in the direction indicated by the arrows (Fig. 15 15 3) within the tubular space 33, as well as outside of the same.

The counter-electrode 31' already mentioned in the preceding paragraph, as well as the hood 34' and the tubular piece 32', are designed precisely as the corresponding parts in the left-hand half of the figure and operate in the same manner. The arrows indicate again the direction in which the extinguishing agent is flowing.

20 The jets which this agent forms and which issue forth from the tubular members 32 and 32' are directed towards one another and impinge upon one another, envelop the arc body in a hose-like fashion and cool it intensely. When the jets 30 impinge upon one another, they are deviated from their straight paths, penetrate into the core of the arc and whirl and agitate the arc thereby.

25 It appears from the foregoing description that two equal jets of the extinguishing agent are 35 used, these jets passing chiefly through the open air. The two jets may so impinge upon one another that they are directed accurately counter to one another which is best effected by arranging the two guide devices for the jets on a common axis. It is, anyhow, also possible to arrange the guide devices at an angle with respect to one another so that the jets impinge upon one another prior to coming in contact with the arc. In this case the arc also is acted on in the intended manner by being whirled and agitated, while at the same time the gas exhaust takes place in a preferred direction.

30 The extinguishing agent may be any desired suitable gasiform or liquid fluid or mixtures 50 thereof. It is particularly suited to the purpose in view to employ compressed air or carbonic acid or a similar substance, although if desired a mixture of air and steam can be used.

35 When making use of a gas under pressure the 55 whirling action is due chiefly to the dynamic effect of the gas particles, but it is, finally, likewise possible to obtain the whirling action upon the arc body by an addition of chemically acting substances.

40 I claim:

1. In the electric circuit breaker art, the method of interrupting an arc formed between coacting electrodes which comprises directing simultaneously from each end of the arc a jet of arc-extinguishing fluid so as to envelop a part of said arc in hose-like fashion, said jets being independent of the arc pressure and in substantial alignment so as to impinge on each other intermediate the ends of the arc.

2. An electric circuit breaker of the fluid blast type comprising relatively movable contacts separable to form an arc upon opening of the circuit, and means independent of the arc pressure for directing two opposing jets of arc-extinguishing 75

- fluid generally longitudinally of said arc, each jet flowing from one of said contacts towards its coacting contact and having a substantially annular cross-section so as to envelop a part of said 5 arc in hose-like fashion, said arc at the point of opposition of said jets being traversed and agitated by said arc-extinguishing fluid.
3. An electric circuit breaker of the fluid blast type comprising relatively movable contact structure separable along a substantially rectilinear path, and means independent of the arc pressure for directing opposing streams of arc-extinguishing fluid along said arc path upon opening of the 10 circuit, said streams being substantially annular 15 in cross-section so as to envelop a part of the arc in hose-like fashion and impinging on each other so as both to traverse and exhaust radially of the arc.
4. An electric circuit breaker of the fluid blast type comprising relatively movable contacts separable to form an arc upon opening of the circuit, coaxial guide means coacting with each of 20 said contacts for directing opposing jets of arc-extinguishing fluid along the path of said arc so 25 as to impinge on each other intermediate the length of said arc, said jets being independent of the arc pressure and substantially annular in cross-section so as to envelop a part of said arc 30 in hose-like fashion.
5. An electric circuit breaker of the fluid blast type comprising relatively movable contact structure separable to form an arc upon opening of the circuit, said structure including a contact pin, coaxial guide means surrounding said pin for 35 directing a jet of arc-extinguishing fluid annular in cross-section longitudinally of said arc so as to envelop said arc in hose-like fashion at said contact pin, and an annular hood member mounted coaxially with respect to said guide means, 40 said hood member having a substantially convex surface with respect to said arc, said surface being generally in alinement with the contact end of said contact pin during opening of the circuit.
6. An electric circuit breaker of the fluid blast type comprising relatively movable contacts separable to form an arc upon opening of the circuit, an insulating sleeve-like member coaxially arranged with respect to each of said contacts to 45 form an annular fluid passage for guiding a jet 50 of arc-extinguishing fluid to said arc, said passages being substantially in alinement and continuous in the closed circuit position of said contacts so that said jets directly oppose each other in the path of the arc, and an annular flared 55 member at the exhaust passage at each of said contacts for guiding radial exhaust therebetween of said arc-extinguishing fluid.
7. An electric circuit breaker comprising relatively movable contact structure including a pair 60 of mutually convex members, the central axes of which are generally in alinement, said contact structure being in engagement at a point along said axes, and means for directing a fluid under pressure centrally of and between said convex
- members upon separation of said contact structure.
8. An electric circuit breaker comprising relatively movable contact structure including a pair of mutually substantially convex members, the central axes of which are generally in alinement, 5 said contact structure being in engagement at a point along said axes and separable to form an arc located between said convex members upon opening of the circuit, and means for directing a fluid under pressure from one of said convex members centrally of and between said convex members upon separation of said contact structure so as to envelop a part of said arc in hose-like fashion. 10
9. An electric circuit breaker comprising relatively movable contact structure including a pair of substantially convex members, the central axes of which are generally in alinement, said contact structure being normally in engagement at a point along said axes and separable to form an arc located between said convex members, means for directing a jet of fluid under pressure from one of said convex members centrally of and towards the other of said convex members, and means for directing in opposition thereto a second jet of fluid under pressure from said other convex member centrally of and toward said first-named convex member, said fluid jets being substantially annular in cross-section so as to 15 envelop a part of the arc in hose-like fashion and exhausting radially between said convex members. 20
10. An electric circuit breaker comprising a pair of relatively movable contacts, a pair of electro-static shields associated with said contacts respectively, said shields having opposed mutually convex surfaces adjacent the point of separation of said contacts, and insulating means for directing a fluid under pressure through and centrally of at least one of said shields to said point of contact separation, said shields being adapted to separate in accordance with the circuit opening operation for directing exhaust of 25 said fluid radially of said contacts between said convex surfaces. 30
11. An electric circuit breaker of the fluid blast type comprising a pair of relatively movable contacts, a pair of electrostatic shields associated with said contacts respectively, said shields having opposed mutually substantially convex surfaces adjacent the point of separation of said contacts, and means for directing a fluid under pressure through and centrally of at least one of said shields to said point of contact separation, 40 said fluid directing means guiding said fluid along a path substantially annular in cross-section so as to envelop the arc at said point of separation, said shields being adapted to separate in accordance with the circuit-opening operation 45 for directing exhaust of said fluid radially between said convex surfaces. 50
